(57) **CLAIM**

The ornamental design for a jumbo size TV remote, as shown and described.

DESCRIPTION

FIG. 1 is a front elevational view of a jumbo size TV remote according to the present invention, in which the broken line shown in this figure is for illustrative purposes only, and forms no part of the claimed design;

FIG. 2 is a right side elevational view thereof;

FIG. 3 is a left side elevational view thereof;

FIG. 4 is a top view thereof;

FIG. 5 is a bottom view thereof;

FIG. 6 is a rear elevational view thereof; and,

FIG. 7 is a front view thereof.
